HOUSING FOR AUTOMATIC TOOTHBRUSH OR THE LIKE

Salvatore P. Aurelio, Chicago Heights, and Efrem M. Ostrowsky, Highland Park, Ill., assignors to Sona Stream Corporation, Peotone, Ill.

Filed Mar. 20, 1970, Ser. No. 21,996

Term of patent 14 years

Int. Cl. D4—02

U.S. Cl. D4—16

FIG. 1 is a perspective view of a housing for automatic toothbrush or the like;

FIG. 2 is a front elevational view thereof;

FIG. 3 is a right-side elevational view thereof;

FIG. 4 is a top plan view thereof;

FIG. 5 is a rear view thereof;

FIG. 6 is a bottom view thereof; and

FIG. 7 is an exploded perspective view thereof.

The left side is substantially a mirror image of the right side.

We claim:

The ornamental design for a housing for automatic toothbrush or the like, as shown and described.
